UNITED STATES PATENT OFFICE.

EDWIN GEORGE FORBES, OF BERKELEY, CALIFORNIA.

DESIGN FOR A COMBINED ASH TRAY AND PIPE REST.

Application filed September 5, 1922. Serial No. 3,626. Term of patent 3½ years.

To all whom it may concern:

Be it known that I, EDWIN GEORGE FORBES, a citizen of the United States, and a resident of Berkeley, county of Alameda, State of California, have invented a new, original, and ornamental Design for a Combined Ash Tray and Pipe Rest, of which the following is a specification, reference being had to the accompanying drawing, forming part thereof.

The figure is a perspective view of the combined ash tray and pipe rest constituting my new design.

I claim:

The ornamental design of a combined ash tray and pipe rest, substantially as shown.

EDWIN GEORGE FORBES.
